UNITED STATES PATENT OFFICE.

SAMUEL W. BOWMAN, OF LANCASTER, PENNSYLVANIA.

DESIGN FOR A KNIFE OR SIMILAR ARTICLE.

Application filed September 7, 1928. Serial No. 28,071. Term of patent 14 years.

To all whom it may concern:

Be it known that I, SAMUEL W. BOWMAN, a citizen of the United States of America, residing at Lancaster, in the county of Lancaster and State of Pennsylvania, have invented a new, original, and ornamental design for a Knife or Similar Article, of which the following is a specification, reference being had to the accompanying drawing forming a part thereof.

The figure is a side elevation of a knife or similar article showing my new design.

The reverse side of applicant's design is ornamented similarly to the side shown on the drawing.

I claim:

The ornamental design for a knife or similar article as shown and described.

SAMUEL W. BOWMAN.
